UNITED STATES PATENT OFFICE.

MELVILLE M. GRAHAM, OF LOS ANGELES, CALIFORNIA.

SAFETY LOCK FOR PINS AND THE LIKE.

Application filed February 15, 1928. Serial No. 254,431.

This invention relates to safety catches for preventing loss of badges, pins and the like, and has for an object the provision of an improved type of safety catch by means of which dislodgment of the badge or pin with which it is used, is practically made impossible after once having been locked in position.

Another object is the provision of a catch as above described, which is adapted to be mounted upon and used in conjunction with the safety catch already in extensive use.

A further object is the provision of a catch of the character described, which, while being positive in operation, is of very simple construction, resulting in low manufacturing cost and ease of operation.

With the foregoing and other objects in view which will be made manifest in the following detailed description and specifically pointed out in the appended claims, reference is had to the accompanying drawings for an illustrative embodiment of the invention, wherein:

Figure 1 is a rear elevation of a badge having one of my improved catches shown in locked position thereupon in conjunction with one of the catches of the type which is already in very extensive use.

Fig. 2 is an enlarged, longitudinal, vertical, sectional view of a portion of the badge of Fig. 1, and catches. The plane of section is taken upon the line 2—2 of Fig. 1 in the direction of the arrows.

Fig. 3 is a transverse, sectional view of a portion of the badge of Fig. 1, showing the catches in end elevation. The direction of view is indicated by the arrow 3 of Fig. 1, and the catches are shown in locked position.

Fig. 4 is a view similar to Fig. 3, with the catches shown in unlocked position.

While my improved catch is shown and described as being utilized in conjunction with a badge, I wish it to be understood that I do not wish to be limited to such use, as the catch is of equal value when used upon pins, brooches, or in fact any article which may be secured to a supporting structure by a pin receivable within a seat after the article has been thus secured.

In its preferred embodiment, my improved catch is especially adapted to be used in conjunction with a catch of the type already in very extensive use. A badge 6 has a securing pin 7 pivoted to the back thereof through the expedient of a pivot pin 8 extending through upstanding ears 9 and through one end of the

pin 7. A seat 11 is aligned with the pivot pin 8, so that when the pin 7 is bent down in substantial parallelism with the badge 6, the free end 12, which is preferably provided with a relatively sharp point, may be received within the seat.

In order to prevent unseating of the free end 12 from the seat 11, the seat 11 is constructed in the form of a trough within the walls of which a locking cylinder 13 is mounted for rotary movement about an axis parallel to or coinciding with the longitudinal axis of the trough. The cylinder 13 is provided with a radial slot 14 extending throughout the length of the cylinder, this slot extending from the center of the cylinder to the circumference. A pair of lugs 16 extend outwards from the cylinder 13 through a slot 17 extending circumferentially of the seat 11, so that the lugs 16 and cylinder 13 may be turned within the seat 11. Thus it may be seen that the cylinder 13 may be turned by means of the lugs 16 so that the slot 14 coincides with the space 18 between the walls of the seat 11. Then, after the end 12 of the pin 7 has been passed through the space 18 to the slot 14, the cylinder 13 may be turned back so that escape of the end 12 from the seat 11 is prevented. This construction is well known, and I lay no claim to the device thus far set forth.

My improved catch, designated as an entirety by the reference numeral 21, comprises a piece of wire having a straight portion 22 mounted for rotary movement about its longitudinal axis within a hole 23 formed in the seat 11, preferably in substantial parallelism with the pin 7 when the pin is seated. The outer end 24 of the wire is upset to prevent displacement of the wire from the hole 23; and the other end 26 of the wire is bent into substantial parallelism with the inner side of the seat 11. The end of the portion 26 of the wire remote from the straight portion 22, is formed into a hook 27 preferably with radius of curvature coinciding with that of the pin 7. The hook portion 27 has its extreme end 28 bent back upon itself far enough so that the distance between the end 28 and the straight portion 22 is less than that between the outer curved portion 27 and the straight portion 22. Thus when the hook 27 is snapped over the pin 7, the end 28 engages the pin 7 and distorts the wire to permit the end 28 to pass over the pin 7. When this has been done, the natural resiliency of the

wire prevents dislodgment of the safety catch 21.

It may thus be seen that both when used by itself and when used in conjunction with the ordinary type of safety catch, my improved catch offers positive means for preventing dislodgment of the badge after the pin 7 and catch 21 have been set in locked position.

10 Various changes in the details of construction may be made without departing from the spirit and scope of the invention as defined by the appended claims.

I claim:

15 1. A lock for a pivotally mounted pin, comprising a seat in register with a portion of said pin, a safety catch comprising a piece of wire having a straight portion mounted for rotary movement about its longitudinal axis adjacent said seat, one end of said wire being bent to provide a hook adapted to engage said pin when received within said seat, the end of said hook being bent back towards said straight portion sufficiently to distort the 20 wire when the hook is positioned upon the pin.

25 2. A lock for a pivotally mounted pin, comprising a seat in register with a portion of

said pin for the removable reception thereof, a safety catch comprising a piece of resilient 30 wire having a straight portion mounted for rotary movement adjacent said seat, one end of said wire being bent to provide a hook adapted to engage said pin when received within said seat, the radial distance from the axis of rotation of said straight portion to the arc traversed by the end of the hook being less than the distance from said axis of rotation of the straight portion to the opposite side of said pin when disposed within the 35 seat.

3. A lock for a pivotally mounted pin, comprising a seat in register with a portion of said pin for the removable reception thereof, a safety catch comprising a piece of resilient 40 wire having a straight portion mounted for rotary movement adjacent said seat, one end of said wire being bent to provide a hook adapted to engage said pin when received within said seat, and resilient means for retaining said hook in engagement with the 45 pin.

In testimony whereof I have signed my name to this specification.

MELVILLE M. GRAHAM.
